KITE

Loran E. Osburn, 7800 E. 91st St., Kansas City, Mo.

Filed Nov. 23, 1964, Ser. No. 82,751

Term of patent 14 years

(Cl. D34—15)

FIG. 1 is a bottom perspective view of a kite embodying my new design;

FIG. 2 is a bottom plan view of same;

FIG. 3 is a top plan view of same; and

FIG. 4 is a side elevational view of same.

The broken line showing of a tail and cord in FIG. 1 are for illustrative purposes only.

I claim:

The ornamental design for a kite, as shown and described.
